(57) **CLAIM**

The ornamental design for a lighting decoration, as shown and described.

DESCRIPTION

FIG. 1 is a top perspective view of a lighting decoration design showing my new design;

FIG. 2 is a bottom perspective view of a lighting decoration design showing my new design;

FIG. 3 is a front view;

FIG. 4 is a rear view;

FIG. 5 is a left view;

FIG. 6 is a right view;

FIG. 7 is a top view;

FIG. 8 is a bottom view;

FIG. 9 is a perspective view of the lighting decoration shown in a configuration of use; and,

FIG. 10 is a perspective view of the lighting decoration shown in another configuration of use.

Any shading and cross-hatching are not features of the design but are utilized to illustrate the surface contours of the lighting decoration design in the drawings.
